VENTILATORS FOR INFLATABLE BUILDINGS
Brian Richard Arnold Reffell, Southall, Middlesex, England, assignor to Specialties Development Corporation, Belleville, N.J., a corporation of New Jersey
Filed Mar. 11, 1965, Ser. No. 438,906
Claims priority, application Great Britain, Mar. 13, 1964, 10,857/64
5 Claims. (Cl. 98—41)

This invention relates to ventilators.

According to the invention there is provided a ventilator comprising a first ventilator part having a number of ventilator orifices therethrough, a second ventilator part rotatably mounted relative to the first ventilator part between first and second positions, lift means on one of the ventilator parts to lift at least a portion of the second ventilator part away from the first ventilator part into a spaced position when the second ventilator part is in its first position and to allow the said portion to return to a close position when the second ventilator part is in the second position, and co-operating sealing means on the first and second ventilator parts to seal the ventilator when the second ventilator is in the close position and to be open when the second ventilator is in the open position.

Preferably the second ventilator part is provided with projections which enter the ventilator orifices when the second ventilator part is in the close position. The projections preferably co-operate with the orifices to form the said sealing means. Additionally or alternatively one of the ventilator parts, preferably the first ventilator part, is provided with an outwardly flanged rim which extends towards and underlies the other ventilator part and the rim seals against the other ventilator part, conveniently with a sealing pad interposed between them.

The sides of the projections, which are preferably frusto-conical in shape, preferably form cam surfaces which co-operate with the edges of the ventilator orifices to form the lift means.

Conveniently, spring means is provided to bias the second ventilator part towards the close position. Alternatively the second ventilator part is relatively flexible so that the said portion thereof flexes into said open position when the second ventilator part is in the said first position.

A number of embodiments of the invention will now be described, by way of example, with reference to the accompanying drawings. In the drawings:

FIGURE 1 is a front view of a ventilator constructed in accordance with the invention,

FIGURE 2 is a sectional view taken along the line 2—2 of FIGURE 1 showing the ventilator in the closed condition,

FIGURE 3 is a plan view of the ventilator shown in FIGURE 1 but in the open condition,

FIGURE 4 is a front view of a modified ventilator in accordance with the invention,

FIGURE 5 is a sectional view taken along line 5—5 of FIGURE 4 showing the ventilator in the open condition, and

FIGURE 6 is a sectional detail view similar to FIGURE 5 of a further modified ventilator shown in the closed position.

Referring first to FIGURES 1 to 3, there is shown a ventilator which may be provided in the side of a building to enable a ventilating air stream to pass therethrough as desired. The ventilator comprises a stationary part 10 and a rotatable part 11 attached together by means of a pivot member in the form of a screw or bolt 12. The parts 10 and 11 are moulded from sheet plastic material, which is resilient but fairly stiff. There are three orifices 13 of equal diameter in the stationary part 10

2

and these orifices are symmetrically positioned about the pivot member. The rotatable part has three projecting formations 14 each of which is in the shape of a shallow, truncated cone having a base diameter substantially equal to the diameter of one of the orifices 13 and the projecting formations are adapted to register with the orifices respectively. In the position shown in FIGURES 1 and 2, in which the projections 14 are in register with the apertures 13, the surrounding peripheral portion 15 of the rotatable part 11 lies close to or against an outwardly projecting flange 16 formed on a peripheral run 10a of the part 10. In this position the ventilator can be said to be closed because air flow therethrough is completely stopped, either by the formations 14 which close the apertures 13 or between the peripheral portion 15 and the flange 16. According to choice the design of the ventilator may be such that either of these restrictions may be used to close the ventilator or both these restrictions may be used.

When the rotatable part 11 is rotated away from the position shown in FIGURES 1 and 2, the conical surface of each projecting formation 14 exerts a camming action on the edge of the respective orifice 13. The projecting formations 14 are thus moved clear of the associated orifices. Further, because of the resilience of the rotatable part 11, its surrounding peripheral portion 15 is deflected away from the flange 16 on the stationary part 10. In the condition when the rotatable part has been rotated through approximately 60° in either direction from the position shown in FIGURES 1 and 2, the orifices 13 are no longer closed by the projecting formations 14 and the peripheral portion 15 is spaced apart from the flange 16 so that air can pass through the ventilator which can then be said to be open.

It can be seen that the resilience of the rotatable part 11 enables it to be distorted in the open position. It is convenient that the stationary part 10 should be made from the same material as the rotatable part 11 and this provides similar resilience in the part 10. Therefore, in the open position the central area of the stationary part 10 is distorted and pulled towards the rotatable part 11 by tension in the screw 12. In the closed position the resilience of the rotatable part 11 urges its sealing parts into engagement to prevent air flow therethrough.

The screw 12 is provided with a nut and washer and after assembly is riveted over. The two parts 10 and 11 may be vacuum formed and the orifices 13 cut subsequently from the stationary part 10. As shown at 17, more particularly in FIGURE 2, the rotatable part is slightly necked so as to strengthen this part at the areas of minimum space between the formations 14.

Referring now to FIGURES 4 and 5, there is shown an alternative form of ventilator 21. This ventilator also comprises a fixed part 22 and a rotatable part 23. These parts 21 and 22 are generally of the same shape and construction as the parts 10 and 11 but are made from a slightly more rigid material. The rotatable part 23 is of approximately the same diameter as the inside of the rim 24 of the fixed part 22 so as to form a continuation of the flange 25. Channels 26 join the projecting formations 26 so as to make the part 23 more rigid.

The two parts 21 and 22 are connected together by a central bolt 27 which passes through a boss 28 formed between the channels 26 in the rotatable part 23. At 65 the end of the bolt 27 there is secured a nut 29 and a washer 30 on the boss 28 and biases the rotatable part 23 towards the fixed part 22. A collar 33 surrounds the bolt 27 between the two parts 22 and 23 to act as a spacer between these two parts so as to prevent distortion 70 of the rotatable part 23 by the spring 31.

In the closed position, the projecting formations 26 seat in the orifices 34 of the fixed part 21 to provide a seal

therewith. On rotation of the rotatable part 22, the projecting formations 26 lift out of the orifices 34 because of the camming effect of the frusto-conical sides of the projecting formations 26 on the edges of the orifices 34. In the open position of the ventilator the projecting formations 26 rest on the portions of the fixed parts between the orifices 34. On further, or return, rotation, the projecting formations 26 snap back into the orifices 34 under the influence of the spring 31 and their sides seal against the edges of the orifices 34 to prevent air flow therethrough.

In a modified form of the ventilator 21, as shown in FIGURE 6, the rotatable member 23a is of larger diameter than the rim 24 of the fixed member 22 and has a portion 23b overlying the flange 25. This portion 23b carries a sealing pad 35 so as to seal against the flange 25 when the ventilator is in the closed position. This seal may be provided in addition to the sealing between the projecting formations and orifices or may be the sole sealing means. In the latter case the projecting formations may be somewhat smaller than the orifices and fit loosely therein so as to act merely as a lifting means. If desired the pad 35 may be omitted and the portion 23b may seal directly on the flange 25.

The ventilators above described are of simple and light construction and are suitable for incorporation in an inflatable building, for example a building which is supported by a structure of inflated tubes.

The ventilator 21 is fixed in position in the canvas or like cover of an inflatable building in the following manner. At each location where it is desired to insert the ventilator 21 the building cover 36 is provided with a circular opening 37 having a diameter sufficient to receive the dished portion of the stationary part 22 but of lesser diameter than the flange 25. This opening 37 is reinforced by a peripheral sewn-in cable 38. An annular draw-sheet 39 surrounds the opening on the inner surface of the cover and forms with the cover a recess for the edge of the flange 25.

When the building is unpacked and ready for erection, the draw sheet 39 is loosened and the dished part is inserted into the opening 37. The draw sheet 39 is manipulated over the flange 25 and tightened, e.g., by a rope 41. The ventilator is now in position ready for the erection of the building. The ventilator is removed in the reverse manner after the inflatable building is deflated and ready for packing. The fixing and removal of the ventilator of

the first embodiment is carried out in the same manner. By removing the ventilator before packing, both the ventilator and the cover are protected against damage when the building is packed.

5 I claim:

1. A ventilator comprising a stationary part having a plurality of circumferentially spaced apertures therein, a rotatable part on said stationary part and having as many circumferentially spaced projections thereon as there are apertures which projections register with and extend into said apertures when said parts are in a first position, and centrally located means for rotatably mounting said rotatable part on said stationary part, said projections having a cam surface on the side thereof for engaging a portion of said stationary part between said apertures to lift said projections out of said apertures upon rotation of said rotatably mounted part to a second position, said parts being constructed and arranged to yield with respect to each other when in the second position, said parts having co-20 operating annular sealing surface means adapted to engage and form a seal when said rotatably mounted part is in the first position.
2. A ventilator according to claim 1, wherein said projections are constructed and arranged to cooperate with said apertures to seal the same.
3. A ventilator according to claim 1, wherein a sealing pad is mounted on one of said sealing surfaces.
4. A ventilator according to claim 1, wherein said parts are constructed of yieldable material to enable said projections to be moved out of said apertures.
5. A ventilator according to claim 1, wherein said mounting means includes spring means for biasing said rotatable part in a direction to cause said projections to enter said apertures.
